UNITED STATES PATENT OFFICE

KNUTE SWANJORD, OF BALATON, MINNESOTA, ASSIGNOR OF ONE-FOURTH TO ERVIL H. ERICKSON, ONE-FOURTH TO OLE A. ERICKSON, AND ONE-FOURTH TO IRA HENSTED, ALL OF BALATON, MINNESOTA

HALTER

Application filed June 20, 1929. Serial No. 372,435.

This invention relates to a halter and particularly to a halter of simple form adapted for use on various animals, including cattle and horses.

5 It is an object of this invention to provide a halter of extremely simple and inexpensive form and yet one which is very convenient and efficient.

It is a further object of the invention to 10 provide a halter made from a strand of flexible material having a bight at its central portion forming the head band and including a nose band detachably connected to said strand, the end portions of said strand being 15 yond said nose band being embraced by a ring and having means adapted to be connected to the sides of said bight in various positions.

It is more specifically an object of the invention to provide a halter formed from a 20 continuous strand of linked chain, said strand having a bight at its central portion constituting a head band of the halter, a nose band having snap hooks or equivalent means 25 at its ends adapted to be connected to the portions of the chain extending from said bight, the end portions of the chain beyond said nose band being embraced by a ring and preferably connected by one or more double 30 and readily detachable links and having snap hooks or equivalent means at their ends adapted to be connected to the sides of said bight in various positions.

These and other objects and advantages 35 of the invention will be fully set forth in the following description made in connection with the accompanying drawings, in which like reference characters refer to similar parts throughout the several views, and in which:—

40 Fig. 1 is a perspective view showing the halter;

Fig. 2 is a partial plan view, and

Fig. 3 is a plan view showing a modified form of the halter.

45 Referring to the drawings, in Figs. 1 and 2 a halter is shown, the principal element of which comprises a continuous strand of linked chain 5. This chain at its central portion has a bight 5a formed therein, which 50 constitutes the head band of the halter.

Portions 5b adjacent said bight constitute the side portions of the halter and these portions have connected thereto respectively the snap hooks 6 secured to the ends of a nose band 7 which is thus detachably connected to the 55 portions 5b. It will be apparent that the snap hooks 6 can be engaged in various links of the chain as desired. Beyond the nose band 7 the end portions 5c of chain 5 are preferably crossed as shown in Fig. 1 and 60 the ends thereof have the snap hooks 8 secured thereto, which are engaged in links of the chain respectively disposed at the sides of the bight 5a. It will be apparent that snap hooks 6 can be engaged in various positions 65 along the chain. The cross portions 5c are embraced by a ring 9 which as shown in Fig. 1 extends transversely of said portions 5c. A lead member such as a rope 10 is secured to the ring 9. 70

In operation the halter will be placed on the animal with the portion 5a extending over the head behind the ears and the nose band 7 will extend across the top of the nose. Portions 5c will then extend beneath the 75 jaws of the animal. With the construction shown it will be seen that should the animal pull backward, the ring 9 will slide toward the nose band 7 and a pinching effect will be secured on the nose of the animal which will 80 help to control the animal. If the animal is being led in a normal manner the ring 9 will adjust itself on the strands 5c so that there will be no discomfort to the animal. It will be apparent that the snap hooks 6 85 and the snap hooks 8 can be engaged in the desired links of the chain 5 to secure a good fit to the halter. A leather or other covering may be placed over the bight portion 5a if desired. 90

In Fig. 3 a modified form of the invention is shown in which a strand of chain 11 is used which has interposed at the central part thereof a leather head band 12 having snap hooks 13 at its ends engaged in the links of chain 11, said head band being divided and having a buckle 14 at the end of one division in which the end of the other division is adjustable. Portions 11a of chain 11 adjacent the head band 12 form the side 95 100

portions of the halter and a nose band 15 provided having snap hooks 16 at its ends adapted to be hooked in the side portions 11a and extend across the same. The end portions 11b of the chain 11 beyond the nose band 15 are embraced by a ring 17 which as shown in Fig. 3 is preferably disposed with one side of the opening toward the nose band 15 and its other side in the opening between the strands 11b. A double link member 18 which comprises a pair of members swinging about a central pivot 19 so as to be readily opened is engaged with the portions 11b adjacent ring 17. Another similar double link 20 is sometimes used particularly if the halter is to be used on a horse when tied in a stall. The ends of portions 11b have the snap hooks 21 secured thereto which may be engaged at various links of the chain adjacent snap hooks 13.

In operation the halter shown in Fig. 3 will be placed on the animal with the portion 12 across the top of the head behind the ears and the nose band 15 will extend across the top of the nose. The ring 17 can be slid on portions 11b until the desired tightness is secured on the nose of the animal and double link 18 can then be placed in position. When ring 17 is disposed as shown in Fig. 3 it does not slide as readily as when disposed as shown in Fig. 2 and member 18 will prevent its sliding backward. The halter thus will remain in position with a good fit around the nose of the animal. If member 20 is used it will be placed in position so that the desired fit is secured around the neck of the animal and portions extending from member 20 to snap hooks 21 will form in effect a throat latch. With such a halter the animal is securely engaged and will not be able to slip the halter over its head.

From the above description it will be seen that applicant has provided a very simple and efficient halter and one which can be very easily and inexpensively made. The halter is readily applied to the animal and can be adjusted to secure a good fit on the animal's head. The halter also forms a good lead halter and one which can control the animal and tend to prevent the same from backing away. The device has been amply demonstrated in actual practice and found to be very successful and efficient.

It will, of course, be understood that various changes may be made in the form, details, proportions and arrangement of the parts without departing from the scope of applicant's invention, which, generally stated, consists in a device capable of carrying out the objects above set forth, in the novel parts and combinations of parts disclosed and defined in the appended claims.

What is claimed is:—

1. A halter comprising a strand of flexible material having detachable hooks at its ends,

said strand having a bight formed at its central portion comprising the head band of said halter, the portions adjacent and extending from said bight forming the sides of the halter, a nose band having detachable connections at its ends secured to said sides, the end portions of said strand beyond said nose band being crossed and said hooks at the ends thereof being connected to said strand at the sides of said bight, and a ring embracing said crossed portions to which a leading member may be connected. 75

2. A halter comprising a single continuous strand of chain having snap hooks at its ends and having a bight formed at its central portion constituting a head band, the portions adjacent and extending from said bight forming the sides of said halter, a nose band having snap hooks at its ends adapted to be variously connected along said side portions in any of the links thereof, the portions of said chain beyond said bight being crossed, the snap hooks at the ends thereof being connected respectively at the sides of said bight, and a ring embracing said crossed portions to which a lead or securing member may be connected. 80

3. A halter comprising a single length of chain having a bight formed at its central portion, a nose band detachably connected to the portions extending from said bight, said chain having detachable connections at its ends connected adjacent the ends of said bight, and a ring embracing the portions of said chain between said nose band and said detachable connections. 95

4. A halter comprising a single length of chain having a bight formed at its central portion, a nose band having quickly detachable means at its ends for attachment in any of the links along the sides of said chain, said chain having detachable connections at its ends connected adjacent the ends of said bight, and a ring embracing the portions of said chain between said nose band and said detachable connections adapted to be connected to a hitch or lead member. 100

In testimony whereof I affix my signature.

KNUTE SWANJORD.
